UNITED STATES PATENT OFFICE

STANLEY D. PAYZER, OF WAUSAU, WISCONSIN, ASSIGNOR TO D. J. MURRAY MANUFACTURING CO., OF WAUSAU, WISCONSIN, A CORPORATION OF WISCONSIN

CHIPPER SPOUT

Application filed February 8, 1932. Serial No. 591,629.

This invention relates to chipping machines used in the manufacture of wood pulp for paper making, and is substantially like standard machines of this class, except for 5 improvements in the means for securely clamping bed knives in place.

The objects of the invention are to provide an improved mounting for chipper spout bed knives whereby the knife may be 10 securely held in its adjusted position and yet rapidly removed and replaced without requiring stoppage of the machine for an undue length of time, as has been necessary with chipping machines. A further object 15 of the invention is to provide an improved means for clamping in a fixed position the bed knives of chipper spouts, which insures clamping contact substantially throughout the entire area of the knife and prevents destructive 20 vibration of the knife such as necessitates frequent changing thereof due to rapid dulling, and avoids the inferior product resulting from the use of dull knives.

The objects of the invention are accomplished by means of a construction such as 25 illustrated in the drawing:

Figure 1 is a side view partly in section of a chipping machine having the improved knife-holding means. 30 Fig. 2 is a side view of the spout portion of the machine illustrating the manner in which the knife-holding wedge is shifted into and out of clamping relation with the knife.

Fig. 3 is a fragmentary detail showing a portion of the wedge in section and as having a guiding flange for fitting an inclined way, whereby the wedge is guided for direction of movement and is supported when 40 in disengaged position.

The type of chipping machine to which this invention relates consists essentially of a frame structure or bed, supporting, in inclined position, a spout into which logs 45 are fed and bear endwise by gravity against a wheel rotating on a horizontal axis and having knives for passing over the face of the spout, and which successively shear disc-shaped sections from the end of the log. 50 The latter extends at an upward inclination

of about 45 degrees from the face of the wheel. The knives of the wheel cooperate with a fixed knife located at the bottom of the chipper spout. The mounting of these knives is vital to the successful operation of 55 the machine. Due to the heavy work performed thereby the bed knives should be clamped rigidly and be as free from vibration as possible; otherwise an inferior product results in which there is sawdust and 60 splinters. Not only have the knives not been satisfactorily mounted in machines of this type, but the manner of mounting them and clamping them in position requires an excessive stoppage of the machine and labor 65 in the replacement and adjustment of the knives.

In the improved machine the stationary knife of the chipper spout is clamped down upon the bed plate by a wedge which moves 70 in a plane a few degrees inclined from the surface of the knife and between the knife and an inclined bearing surface above the wedge. The structure is heavy and rigid, and assures the clamping of the knife substantially throughout its area and close to 75 the cutting edge. Provision is made for rapidly actuating the wedge in order to reduce the time required for changing knives and thus encourages the more frequent 80 changing thereof, and improves the quality of the chips.

Referring to the drawing the base or frame structure 1 of the machine supports at one end a chipper spout 2 and at the opposite end a motor 3 including a bearing 4, for a horizontal shaft 5, which is driven by the motor and carries a knife wheel 6. The opposite end of shaft 5 is supported by the part 7 of the base structure at one side of 85 the chipper spout. The knives 8 of wheel 6 extend from near the axis of the wheel toward the periphery thereof sufficiently to span the mouth 9 of the chipper spout which is eccentric to the axis of the wheel, and 90 inclines upwardly about 45 degrees.

The chipper spout has the usual wear plates 10 and 11, and is provided with a bed plate 12, resting upon and clamped to the part 7 of the machine frame. The lower 100

wall 13 of the chipper spout terminates in the enlarged foot 14 bridged over the bed plate 12 at the location of the bed knife 15. The lower surface 16 of the foot of the 5 spout is flat and somewhat inclined from the horizontal to provide the upper bearing surface for a wedge 17. This wedge has flanges 18 at its sides fitting grooves 19, formed in the foot 14 of the spout. These 10 grooves are parallel to the surface 16.

The wedge is provided with rearwardly extending ears 20 in which are supported fixed thereto pins 21 which pass through forked ends of arms 22 carried by horizontal 15 shafts 23, journaled in the side wall supports 24 for the chipper spout.

An operating lever 25, Figure 2, is carried by shaft 23 and by means of this lever the wedge may be withdrawn from the bed 20 knife to allow removal of the latter. In order to lock the lever 25 and to firmly drive the wedge into knife-securing position the lever 25 carries pivoted thereto a forked arm 26 having the threaded end 27 passed 25 through a notch 28 at the upper end of a fixed bracket 29. By tightening a nut 30 the lever 25 may be drawn with considerable leverage rearwardly, thus forcing the wedge forwardly as far as it will go. In order to 30 release the wedge it is only necessary to loosen nut 30, rock the element 26 out of notch 28 and shift the lever 25 forwardly.

Adjustment of the bed knife 15 with reference to the knives on wheel 6 may be effected in the customary manner by rods 31 which, at their inner ends 32, have T-heads fitting within T-slots in the knife, and at their opposite ends pass through slots 33 in a transverse flange 34 extending between the 40 web-like extensions 24 of the side walls of the spout. The rods 31 are threaded at the end 35 to receive nuts 36 and 37 whereby they may be finally adjusted fore and aft to properly seat the bed knife 15. The cutting end 38 of the knife is sharpened at right angles to the plane of the knife in order that the latter will be reversible.

In the operation of changing one of the 50 knives 15, lever 25 is released by loosening nut 30, Fig. 2, the member 26 is swung upwardly and the lever is then manually shifted in a forward direction thus withdrawing the wedge 17 from the upper surface of knife 15. The wedge is guided in 55 this movement by the inclined grooves 19 within which the wedge flanges 18 fit. The wedge is thus retained out of contact with the knife. Nuts 36 and 37 are loosened and the rods 31 are swung upwardly clear 60 of flange 34 while being drawn rearwardly and pulling the knife out of the machine.

The new knife is then fitted to the T-heads of the rods 31 and pushed into place and closely adjusted by manipulation of the 65 nuts 36 and 37 which finally serve to lock

the knife in the adjusted position. Then the knife is rigidly clamped in such position by drawing the lever 25 backwardly as far as it will go, the element 26 being dropped into the notch in bracket 29 and the lever is 70 locked by tightening the nut 30.

Although but one specific embodiment of this invention is herein shown and described, it will be understood that details of the construction shown may be altered or omitted without departing from the spirit of this invention as defined by the following 75 claims.

I claim:

1. A chipping machine comprising a supporting structure having a rigidly mounted spout, a chipping wheel mounted for rotation upon the supporting structure and provided with a chipping knife, means for driving said chipping wheel, a stationary knife adjacent the end of the spout, a support upon which the knife rests, means providing a wedge bearing having a surface opposite said knife support and inclined with reference to the surface of said knife support, and a wedge fitting between said bearing surface and the knife and engaging the knife throughout the major part of the surface of the knife with which it contacts. 80

2. A chipping machine comprising a supporting structure having a rigidly mounted spout, a chipping wheel mounted for rotation upon the supporting structure and provided with a chipping knife, means for driving said chipping wheel, a stationary knife 85 adjacent the end of the spout, a support upon which the knife rests, means providing a wedge bearing having a surface opposite said knife support and inclined with reference to the surface of said knife support, a 90 wedge fitting between said bearing surface and the knife and engaging the knife throughout the major part of the surface of the knife with which it contacts, and means for adjusting and locking the wedge. 95

3. A chipping machine comprising a supporting structure having a rigidly mounted spout, a chipping wheel mounted for rotation upon the supporting structure and provided with a chipping knife, means for driving said chipping wheel, a stationary knife adjacent the end of the spout, a support 100 upon which the knife rests, means providing a wedge bearing having a surface opposite said knife support and inclined with reference to the surface of said knife support, a wedge fitting between said bearing surface and the knife and engaging the knife throughout the major part of the surface of the knife with which it contacts, means for 105 adjusting and locking the wedge, said means comprising a pivoted lever having at one end a pivotal connection with the wedge, an arm pivoted to said lever, a fixed bracket having 110 an opening through which said arm extends, 115

120

125

130

and threaded means for engaging said arm and the bracket for adjusting the arm and lever.

4. A chipping machine comprising a supporting structure having a rigidly mounted spout, a chipping wheel mounted for rotation upon the supporting structure and provided with a chipping knife, means for driving said chipping wheel, a stationary knife adjacent the end of the spout, a support upon which the knife rests, means providing a wedge bearing having a surface opposite said knife support and inclined with reference to the surface of said knife support, a wedge fitting between said bearing surface and the knife and engaging the knife throughout the major part of the surface of the knife with which it contacts, and guiding means for the wedge arranged for guiding the wedge into and out of engagement with the knife and for supporting the wedge when disengaged from the knife.

Signed at Wausau, in the county of Marathon and State of Wisconsin, this 23rd day of January, 1932.

STANLEY D. PAYZER.
